UNITED STATES PATENT OFFICE.

SAMUEL L. McCORMICK, OF PITTSBURGH, PENNSYLVANIA, AND WILLIAM F. RESE,
OF WARREN, OHIO.

METHOD AND MACHINERY FOR FORMING STRIP METAL.

1,294,501.

Specification of Letters Patent. Patented Feb. 18, 1919.

Application filed May 8, 1917. Serial No. 167,172.

To all whom it may concern:

Be it known that we, SAMUEL L. McCORMICK, residing at Pittsburgh, in the county of Allegheny and State of Pennsylvania, 5 and WILLIAM F. RESE, residing at Warren, in the county of Trumbull and State of Ohio, both citizens of the United States, have invented or discovered certain new and useful Improvements in Methods and 10 Machinery for Forming Strip Metal, of which improvements the following is a specification.

Our invention relates to improvements in method and in machinery for forming strip 15 metal. The method is accomplished in the operation of our improved machine; and the machine in its coördinated movement subjects the material to the working of our improved method.

20 The invention is applicable in the production of strips of metal of all sorts—of steel, iron, copper, brass, aluminum, or of any other metal; we have actually applied it in the production of steel strip, and shall describe it in that particular application. In view of the ensuing explanation, these skilled in the production of other metals will be able to adapt our invention to their needs.

25 The machine is shown in the accompanying drawings. Figure 1 is a view of the entire machine in plan; Fig. 2 is a view in vertical section, on the plane indicated by the line II—II, Fig. 1. In this view many of the parts appear in side elevation.

30 The machine includes and consists of essentially a slitter 1, a rolling mill 2, a reel 3, and shears 4. These are arranged in alignment, in a common line of progress of the work, A—B.

35 The slitter 1 shown is a rotary slitter, and includes one and preferably two cylindrical bodies, one at least of which is provided with sharp-edged collars constituting rotary knives or cutters. These collars will preferably be removable and replaceable upon the cylindrical carrier and adjustable in their actual and relative positions thereon. Slitters of this character and possessing 40 these features are well known, and we have not therefore thought it necessary in our drawings to show details of the slitter in these particulars. Any slitter of any particular character or construction, adapted to 45 the ends to be described, will serve.

The rolling mill 2 is a mill for cold rolling. It ordinarily will be adjusted to reduce the thickness of the material passing through, by as much as .005 to .010 of an inch. It is effective to roll and finish the 60 strip, and to remove the bur which in the slitting operation has been developed on the edge of the strip.

The reel 3 may be of any particular form desired, but will be arranged for taking up 65 the material directly and by continuous operation, as it passes from mill 2.

The shears 4 are arranged preferably beyond and somewhat above the level of the advance of work to the reel. This is best 70 shown in Fig. 2. The reel and the shears are arranged and intended to be brought into service alternately: when the reel is acting the shears are idle, and, contrariwise, when the shears are acting the reel is idle. 75 The reel is arranged at a lower level as a matter of convenience, to the end that, when the reel is to be put out of action and the shears are to be brought into action instead, a conveyer 8 (indicated in Fig. 2 in dotted 80 lines) may be laid, extending above the reel and leading directly from the mill 2 to the shears 4.

The slitter, mill, and reel are, it will be observed, mounted conveniently on a common base; they are driven from a common source of power. This source of power may be such as is convenient; here we have shown as a suitable source the electric motor 5. The slitter 1 is directly and positively driven 90 from the source of power, and the mill 2 and the reel 3 are geared to the slitter drive, to be operated with it. These parts, slitter, mill and reel are necessarily spaced apart sufficiently to provide for such a driving arrangement, and to afford access to all parts of the machinery; but, otherwise, it will be observed that the parts are in immediate space relationship, so that the material passes in continuous operation through the 100 entire succession of instrumentalities. And, furthermore, the shears 4, though in the installation shown they are not driven from the same source of power, and are not shown to be mounted on a common base with the 105 other parts, are, nevertheless, arranged adjacent the other parts, and immediately beyond the reel, to the end that they may receive the material as it advances from the mill 2.

All these four parts, so alined, are furthermore preferably so arranged and are here shown to be so arranged that they receive and deal with the material without deflecting it from the direction of its extent. As shown, the material as it is received extends horizontally, and in that position it remains throughout its progress through the machine.

10 It remains to be noted that, in the line of drive from the source of power 5 to the mill 2, and also in the line of drive to the reel 3, variable speed clutches 6, 7 are arranged, and these are provided with suitable manually operable control (not shown), to the end that the relative speeds of mill to slitter, and of reel to slitter, and of reel to mill as well, may be properly and accurately controlled and adjusted. It is possible, mani-
20 festly, to make one or the other of the elements, the mill and the reel, the positively driven member, and to introduce the speed-altering means in the lines of drive of the other two elements; and, indeed, it is pos-
25 sible and practicable to introduce such a speed-varying means in the line of drive from the source of power to each of the three elements, slitter, mill, and reel. But we have found the arrangement shown and
30 first described to be serviceable, and we believe it to be best. As to the clutch 7, inter-
posed between the source of power and the reel 3, it may, in addition to its capacity to effect variation in speed, be capable of be-
35 ing opened entirely, to the end that the reel 3 may be stationary while slitter and mill travel. Manifestly, there is no need to have the reel turn when it is not needed, and this will be the case when the finished strip, in-
40 stead of being fed to the reel, is fed to the shears 4.

Directing attention now to the coöperative action of slitter and rolling mill, it will be manifest that, in dealing with strip material of ordinary length, the material under treatment will, during substantially all of the operation, be subjected at closely adjacent points in its length and simultaneously to the action of these two machine elements; and it will be understood that by nice adjustment of relative speed, such as can be attained by instrumentalities of the nature indicated, the material as it passes through the slitter may be held under a tension pro-
45 duced by the tractive effect of the mill, and thus be kept taut and straight and free of the warping twisting and distortion which are incident to the slitting of such material as it is ordinarily conducted. It will be ob-
50 served, furthermore, that intermediate han-
dling of the strip and such intermediate operations as are commonly resorted to—pick-
ling, annealing, etc.—are dispensed with.
55 And this with considerable economic ad-
vantage. Intermediate annealing has here-

tofore been considered necessary, after slitting, and preliminarily to cold-rolling, in order to take the kink out of the material, and also to accomplish the rolling away of the bur raised by the slitter on the edge of the strip. As we have said, our coördination of machinery and correlation of method prevent kinking, and the removal of the bur and the cold-rolling of the strip become possible in a single operation, continuous with the slitting—a practice not heretofore achieved.

In addition to the parts previously described, the drawings show edging rolls 9, arranged on the feed side of rolling mill 2, and between slitter and mill; these are effective to more accurately define and determine the path of the strip. Preferably the rolls 9 are idle as shown. The drawings show also a flattening device 10, situated beyond the mill 2 and on the feed side of the shears 4; such a flattening device is useful, in case the finished article is to be sheared into uncoiled lengths, to cause the extended lengths to lie smooth upon the support pro-
90 vided to receive and sustain them.

The operation in all its parts may be more fully described in a few words. The machine, previously synchronized, is set in motion. The strip material in the rough—
95 that is to say, somewhat oversize both in width and in thickness—properly annealed, is introduced through the slitter 1, and, in continuous advance, through the mill 2, and its forward end properly secured in reel 3. 100 As operation progresses, relative speeds may be more minutely adjusted by the operator. As between mill and slitter the relative speeds will be such as to afford the tension desired for the ends already indicated; as between reel and mill, adjustment will of course be made as the coil of finished material heaps up on the reel. In the slitter the material will be trimmed and separated into one or more strips of proper width; in the mill this slitted material will be rolled to the desired thickness (with corresponding extension in length) and the burs raised by the cutting edges of the slitter will be rolled out. The reel of course will take the finished strip from the mill.

Instead of winding the finished strip on the reel, it may, however, be caused to advance upon conveyer 8 above and beyond the reel and to enter the shears, where it may as it advances be severed into suitable lengths.

The advantages incident to and characteristic of our invention are, first of all, manifestly, very appreciable economy in 110 floor-space; but, beyond that, the notable advantage is the slitting and rolling of strips in continuous operation, together with real-
115 ing or shearing, alternatively, as may be de-
sired; a further incidental advantage is 120
125

found in the removal of the bur from the edge of the slit strip in continuous operation with slitting.

The machine of our invention in its operation saves and dispenses with the services of several men otherwise needed. We can take a plain hot-rolled pickled strip and reduce it in thickness as much as from five to ten thousandths of an inch, in one and the same operation with the slitting to exact an ultimate width, and in so doing produce an article which, as well as being correct in width and thickness, is in finish equal to a full pickled and cold-rolled sheet.

15 We claim as our invention:

1. The step in the method of forming strip metal herein described, which consists in successively shearing the strip from a wider blank of material and rolling the sheared strip for the removal of the bur formed during such shearing and in subjecting the material while in the shearing operation to tension derived from the rolling operation whereby the strip is held against distortion while being sheared.

2. An improvement in the method of making strip metal which consists in subjecting a suitable blank to successive operations of slitting and of rolling it for the removal of the bur formed during the slitting operation, and in such treatment holding the material at the point of slitting under tension due to the rolling whereby the strip is held against distortion while being slit.

35 3. In machinery for forming metal strip, the combination of a slitter and a rolling mill arranged in a common line of feed, means for driving said slitter and said mill, and means effecting variation in the speed of one of said parts with respect to the other.

40 4. In machinery for forming metal strip, the combination of a rotary slitter and a rolling mill arranged in a common line of feed, a source of power, operative connection

between said source of power and said slitter, operative connection between said source of power and said mill, and a speed variation device interposed in the operative connection between the source of power and the mill.

5. In machinery for forming metal strip the combination of a rotary slitter, a rolling mill, and a reel, all arranged in a common line of feed, means for driving the three said parts, and means for effecting variation in relative speed between mill and slitter and means for effecting variation in relative speed between reel and mill.

6. In machinery for forming metal strip, the combination of a rotary slitter, a rolling mill, a reel, and shears, all arranged in a common line of feed, means for driving said slitter, mill, and reel, and means for effecting variation in relative speed between slitter and mill.

7. In machinery for forming metal strip, the combination of a rotary slitter, a rolling mill, a reel, and shears, all arranged in a common line of feed, means for driving said slitter, mill, and reel, means for effecting variation in relative speed between slitter and mill, and means for disconnecting said reel from said driving means.

8. In machinery for forming metal strip, the combination of a slitter and a rolling mill arranged in a common line of feed, means for driving the said slitter and said mill, means for effecting variation in the speed of one of said parts with respect to the other, and edging rolls arranged intermediate said slitter and said rolling mill.

In testimony whereof we have hereunto set our hands.

SAMUEL L. McCORMICK.
